(57) **CLAIM**

The ornamental design for a rotary hammer, as shown and described.

DESCRIPTION

FIG. 1 is a front perspective view of a rotary hammer with battery pack attached showing a first embodiment of our new design.

FIG. 2 is a left side elevational view of the first embodiment.

FIG. 3 is a right side elevational view of the first embodiment.

FIG. 4 is a front elevational view of the first embodiment.

FIG. 5 is a rear elevational view of the first embodiment.

FIG. 6 is a top plan view of the first embodiment.

FIG. 7 is a bottom plan view of the first embodiment.

FIG. 8 is a front perspective view of a rotary hammer without the battery pack attached showing a second embodiment of our new design.

FIG. 9 is a left side elevational view of the second embodiment.

FIG. 10 is a right side elevational view of the second embodiment.

FIG. 11 is a front elevational view of the second embodiment.

FIG. 12 is a rear elevational view of the second embodiment.

FIG. 13 is a top plan view of the second embodiment; and,

FIG. 14 is a bottom plan view of the second embodiment.
